UNITED STATES PATENT OFFICE.

CHARLES HATTER, OF LANCASTER, OHIO.

SPREADER.

1,099,362.

Specification of Letters Patent.

Patented June 9, 1914.

Application filed February 26, 1914. Serial No. 821,251.

To all whom it may concern:

Be it known that I, CHARLES HATTER, citizen of the United States, residing at Lancaster, in the county of Fairfield and State 5 of Ohio, have invented certain new and useful Improvements in Spreaders, of which the following is a specification, reference being had to the accompanying drawings.

This invention relates to certain improvements in spreaders and has relation more particularly to a device of this general character especially designed and adapted for use in connection with hay or the like; and the object of the invention is to provide a 15 device of this general character having novel and improved means whereby the same may be employed with convenience and facility for conveying hay or the like from a wagon to a hay mow or other dumping place.

20 The invention consists in the details of construction and in the combination and arrangement of the several parts of my improved spreader whereby certain important advantages are attained and the device is rendered simpler, less expensive and otherwise more convenient and advantageous for use, all as will be hereinafter more fully set forth.

The novel features of the invention will be 30 carefully defined in the appended claim.

In order that my invention may be the better understood, I will now proceed to describe the same with reference to the accompanying drawings, wherein is set forth a 35 view in elevation of a device constructed in accordance with an embodiment of my invention.

As disclosed in the accompanying drawings, 1 denotes a ring or eye member adapted to afford a convenient means whereby the device may be coupled or connected with the hoisting rigging (not shown) which may be of any form of construction desired.

2 denotes the spreader or cross bar of pre- 40 determined length operatively connected to the ring or eye member 1 by the link members 3, the lowermost of such members being secured to the extremities of such spreader or cross bar 2, as is believed to be clearly ob-

vious. As herein disclosed, the extremities 50 of the spreader or cross bar 2 are directed through the rigid eye members 4 formed on the lower link members 3 and also suitably engaged with the eye members 4 are the fork members 5 of the conventional double-harpoon type, certain of the prongs of each of such forks being provided with the trip levers 6 operatively connected one with the other whereby they will operate in unison. The connected trip levers of each of the 60 forks are operatively connected to an extremity of a flexible member 7 common to both and suitably engaged with such flexible member 7 is a trip rope 8 of predetermined length whereby it will be seen that both of 65 the forks 5 may be manipulated to drop or deposit their load in unison.

As herein disclosed, I have the trip rope 8 loosely connected with the flexible member 7, as is indicated at 9, the independent movement of such connection 9 being limited by a suitable stop 10 positioned at either side of the connection 9, as is believed to be clearly shown in the accompanying drawings.

As is believed to be obvious, the cross bar 75 or spreader 2 serves to maintain the forks 5 in fixed spaced relation whereby they may be employed with greater convenience in engaging the hay or the like whereby, as is thought to be obvious, the hay or the like 80 may be lifted from the wagon and dropped or deposited in the mow with greater convenience and facility.

From the foregoing description, it is thought to be obvious that a spreader constructed in accordance with an embodiment of my invention is of an extremely simple and comparatively inexpensive nature and is particularly well adapted for use by reason of the convenience and facility with which 90 it may be assembled and by reason of the effectiveness with which it performs its requisite functions, and it will also be obvious that my invention is susceptible of some change and modification without material departure from the principles and spirit thereof and for this reason I do not 95 wish to be understood as limiting myself to

the precise arrangement and formation of the several parts herein shown in carrying out my invention in practice.

I claim:

- 5 A spreader of the character described comprising a ring, links engaged with said ring and being provided with rigid eyes, an elongated spreader arm having its extremities disposed through the eyes of the links, and

hay forks pivotally engaged with the eyes 10 of the links.

In testimony whereof I hereunto affix my signature in the presence of two witnesses.

CHARLES HATTER.

Witnesses:
